MAGNETOMETER HEAD

Walter H. Brattain, Chatham, N. J., and Norman E. Klein, Garden City, and Max S. Richardson, Huntington, N. Y., assignors to the United States of America as represented by the Secretary of the Navy.

Application May 11, 1944, Serial No. 535,158

2 Claims. (Cl. 177—380)

1

This invention relates to magnetometer heads and more particularly to magnetometer heads arranged for use with magnetic stabilization systems of the type disclosed in copending application Serial No. 529,003, filed March 31, 1944, Magnetic Stabilization System, Donald G. C. Hare.

As disclosed in the copending case above referred to, a detector-magnetometer element, which may comprise one or more magnetic strips with appropriate coils, may be held in alignment with a relatively uniform magnetic field by means of orienting systems controlled by a pair of auxiliary magnetometers, the magnetometer elements of which are conveniently arranged with their axes mutually perpendicular and perpendicular to the axis of the detector-magnetometer element. Also, as disclosed therein, the auxiliary magnetometer elements are mounted on the structure supporting the detector-magnetometer element and move therewith.

In the construction of a magnetometer head meeting the requirements of the system above described, it is ordinarily desired to produce a magnetometer head having at once compactness and freedom from interaction between the various magnetometer elements. Such interaction includes modulation of the output of the detector-magnetometer element by the orientor-magnetometer elements and the converse effect. Heretofore, such interaction has been reduced to a satisfactory amount only by providing considerable spacing between the several magnetometer elements. Such spacing is, of course, highly undesirable in portable magnetometers in that it increases their size and weight and multiplies the problems encountered in mounting such magnetometer heads in position for operation.

In view of the above, objects of the present invention are to provide a magnetometer head adapted for use with magnetic stabilization systems which may be made more compact than those heretofore used without increasing interaction between the magnetometer elements, and to provide a magnetometer head such that assembly and adjustment for minimum interaction are facilitated.

Accordingly, it is a feature of the invention to provide a magnetometer head comprising paired orientor-magnetometer elements arranged in a plane in square configuration, a detector-magnetometer with its axis extending through and substantially perpendicular to the plane of the configuration substantially in the center thereof, the distance from the longitudinal center of the detector-magnetometer element to this plane being substantially zero.

The above and other features of the invention will be pointed out in the following detailed description and in the appended claims.

In the drawing, the single figure is a perspective

view of a magnetometer head according to the invention.

As shown in the drawing, the several magnetometer elements are mounted on a plate 10, which is supported by a gimbal system shown schematically for movement about mutually perpendicular axis A—A' and B—B'. Orientor-magnetometers each comprising a pair of magnetometer elements control motions of plate 10 about these axes. 10 Thus, magnetometer elements 12 and 14 comprise the control portion of one orientor-magnetometer and control the rotation of plate 10 about axis B—B', while elements 16 and 18 comprise the control portion of the other orientor-magnetometer and control the rotation of plate 10 about axis A—A'. These magnetometer elements are mounted in pairs on plate 10 substantially in square configuration. As indicated in the drawing, magnetic strip members 20 of the four orientor-magnetometer elements are so mounted that they form a substantially closed magnetic path about the periphery of plate 10. Thus, the magnetic circuit of each pair of the orientor-magnetometer elements is in effect provided with a return path of relatively low reluctance which substantially increases its apparent permeability and thus its sensitivity without requiring any increase in size. This construction is particularly advantageous when the two magnetometers are so operated that the magnetic flux travels continuously around the magnetic circuit. It will be understood, however, that the orientor-magnetometers may be connected to operate otherwise and that a continuous magnetic path may not always be necessary. In any event, the placement of the wiring to the several magnetometer elements should be such that there are no linking turns which might introduce undesirable interactions.

40 Tube 22 supports the detector-magnetometer element which is mounted therein with the axis of symmetry of the array in alignment with the axis of the tube, the details of the mounting depending upon the type of detector element used. 45 The tube extends through a hole in plate 10 having a diameter substantially greater than that of the tube and is supported substantially normally to the plate by means of a mounting to be described below. For minimum interaction, the tube 22 must be substantially perpendicular to the plane of the orientor-magnetometer element array and substantially at the center thereof. In addition, to achieve compactness, tube 22 should be only slightly longer than the elements and the longitudinal center of the elements within the tube should lie in or very close to the plane of the orientor-magnetometer element array. Furthermore, since the magnetic axis of a magnetometer element may not coincide exactly with the geometrical axis thereof, and since the

orientor-magnetometer element array may not be exactly square, the mounting for detector-magnetometer element tube 22 referred to above must provide means for varying the point at which the axis of tube 22 intersects the plane of the orientor-magnetometer array. Means must also be provided for adjusting the relative position of the midpoint of the detector-magnetometer element array in respect to the plane of the orientor-magnetometer element configurations. Either of these adjustments may be more important than the other, depending upon the type of detector-magnetometer element used. Furthermore, means must be provided for adjusting the angular position of the detector-magnetometer element array about its axis of symmetry.

If the detector-magnetometer element array is such that it has a symmetrical magnetic field, the first described adjustment is the more important although the other two must be given some consideration. If, on the other hand, the magnetic field of the detector-magnetometer array is nonsymmetrical, the rotational adjustment becomes more important. In general, all three must be considered but only one will be critical for any particular type of detector magnetometer.

To provide the desired adjustments, tube 22 is supported by split bushing 24, which is clamped thereto by means of a screw 26 extending normal to and across the split portion of the bushing to a nut 27 recessed in a wall of the bushing. Bushing 24 rests on plate 10 and may be clamped against the plate by means of clamp ring 28 which is drawn to plate 10 by means of bolts 30 extending therethrough to nuts 32. Since the opening in plate 10 is of greater diameter than that of tube 22, the latter may be moved laterally within a limited range. Control of such motion is by means of a pair of perpendicularly disposed lateral adjustment screws 34 and 35, which act against lateral adjustment nuts 36, mounted on plate 10. Extensions on screws 34 and 35 extend through openings in split bushing 24 and are flared over in such a manner that the screws may rotate in respect to the bushing, but may not move axially without causing lateral movement thereof. The holes in the bushing through which the screws extend are somewhat larger in diameter than the screws, and nuts 36 are mounted on plate 10 for pivotal motion, thus minimizing interaction between the two adjustments. Appropriate adjustments of screws 34 and 35 alter the point at which the axis of tube 22 intersects the plane of the orientor-magnetometer element configuration.

The two adjustments provided by the lateral adjustment screws are substantially independent, and split bushing 24 and clamp ring 28 are so arranged that these adjustments may be made without altering the position of the longitudinal center of tube 22 in respect to plate 10. After the components of the head have been assembled as shown in the drawing, adjustments are made in the following manner. Adjustments of the position of the longitudinal center of the detector-magnetometer element array in respect to plate 10 are made by loosening screw 26 to unclamp tube 22, and moving that tube axially until the position at which interactions are minimum is located. Thereafter, screw 26 is retightened. For lateral adjustments, screws 30 are loosened just sufficiently to free bushing 24 for lateral movement over plate 10. Using ap-

propriate output measuring instruments, interaction between detector-magnetometer element array 22 and orientor-magnetometer elements 12 and 14 are reduced to a minimum by adjustment of lateral adjustment screw 34. Thereafter, interactions between the detector-magnetometer element and orientor-magnetometer elements 16 and 18 are reduced to a minimum by adjustment of lateral adjustment screw 35. In general, minor readjustment of screw 34 may be required before the desired results are obtained. Screws 30 are then tightened to complete this adjustment procedure.

Since strains causing deformation of magnetic strip members 20 of the orientor-magnetometer elements result in distortion in the magnetic fields thereof, it is desirable that these magnetometer elements be so mounted on plate 10 that no unbalanced forces are exerted thereon. If the strips are forced, in mounting, to assume positions other than those they would assume under their own weight on a flat surface, the magnetic field of the orientor-magnetometer configuration is badly distorted and interaction with another magnetometer in the same region is increased. Interaction so caused may be very difficult to reduce by mechanical adjustment and is to be avoided. Accordingly, strain in strips 20 is minimized by making plate 10 of a material at once relatively free from a tendency to warp and having a temperature coefficient of expansion similar to that of the magnetic strips, as for example Mycalex, and providing in its surface milled grooves adapted to receive strips 20 without causing appreciable distortion thereof.

Having thus described our invention, what we claim as new and desire to secure by Letters Patent of the United States is:

1. A magnetometer head comprising paired orientor-magnetometer elements arranged substantially in a plane in square configuration and connected to form a closed magnetic circuit, a detector-magnetometer element disposed within said closed magnetic circuit with its axis extending through and substantially perpendicular to said plane, means for varying the point of intersection of the axis of said detector-magnetometer element with said plane, and means for varying the distance from the longitudinal center of said detector-magnetometer element to said plane.

2. A magnetometer head comprising orienting and detecting magnetometer elements, means for mounting the orientor-magnetometer elements in a plane with their cores forming a closed magnetic circuit and in such manner that there are no unbalanced forces acting on said cores, and means for adjustably mounting the detector-magnetometer element symmetrically in the plane of the orientor-magnetometer elements at a point where the interaction of their magnetic fields is a minimum.
